MOP HEAD HOLDER

Roy A. Myers, St. Paul, Minn.

Application January 16, 1933, Serial No. 651,903

1 Claim. (Cl. 15—153)

My invention has for its object the provision of an extremely simple and highly efficient mop holder for attaching a mop head or swab to a mop stick.

5 To the above end, the invention consists of the novel devices and combinations of devices hereinafter described and defined in the claim.

In the accompanying drawing, which illustrates the invention, like characters indicate like parts 10 throughout the several views.

Referring to the drawing:

Fig. 1 is a plan view of the improved mop head holder with some parts broken away and sectioned and holding a mop head fragmentarily illustrated by means of broken lines;

Fig. 2 is a view corresponding to Fig. 1, with the exception that some parts are shown in different positions by both full and broken lines;

Fig. 3 is a sectional view taken on the line 3—3 20 of Fig. 1;

Fig. 4 is an elevation of the outer end of the improved mop head holder with the relatively fixed clamping bar shown in another position by means of broken lines; and

Fig. 5 is a view partly in elevation and partly in section taken on the line 5—5 of Fig. 2.

The numeral 6 indicates a mop stick, to one end of which is rigidly secured the improved mop head holder. This mop head holder comprises a fork 7, a relatively fixed clamping bar 8, a relatively movable clamping bar 9, and a screw-threaded operating rod 10 to which is applied a co-operating thumb-nut 11. A mop head Z, diagrammatically illustrated by means of broken lines in Fig. 1, is inserted between the clamping bars 8 and 9, which are partly separated. Obviously, by turning the thumb-nut 11, in the proper direction on the screw rod 10, the movable clamping bar 9 will be moved bodily toward the fixed clamping bar 8 to hold the head Z tightly clamped therebetween.

The fork 7 is made up of a pair of flat metal bars and a pressed metal crown piece 12, that is channel-shaped in cross-section. These bars are shaped, at one of their end portions, to form the two prongs 13 of the fork 7, which prongs are parallel and the intermediate portions of said bars are in converging relation and form, together with the crown piece 12, the transverse portion of the fork 7. The other or inner end portions of the bars are parallel and one end portion of the stick 6 projects therebetween and is rigidly secured thereto by a pair of rivets 14. The bars, at the transverse portion of the fork 7, extend through the end portions of the crown piece 12,

and the sides of said piece are folded thereover to rigidly secure the crown piece 12 to the bars.

A hole 15 for a purpose that will presently appear, is formed in the bottom of the crown piece 12 in axial alignment with the stick 6. The free end portions of the prongs 13 are reduced in transverse width, see Fig. 4, and bent laterally toward each other to afford a pair of retaining lugs 16. The clamping bars 8 and 9 extend endwise between the prongs 13 and each thereof, in cross-section, is in the form of a yoke of such transverse dimensions as to permit the fixed clamping bar 8 to seat within the movable clamping bar 9. Both clamping bars 8 and 9 are inward of the lugs 16, and the fixed clamping bar 8, at its end 10 portions, straddles said lugs and is normally held thereby against outward movement. A hinge pin 17 connects the fixed clamping bar 8, at one of its ends, to one of the lugs 16, for outwardly swinging movement in the plane of the fork 7 when released from the other of said lugs.

The fixed clamping bar 8 has sufficient loose play at its hinge pin 17 to permit said bar, when its free end portion is lifted out of interlocking engagement with the respective lug 16, as indicated by broken lines in Fig. 2, to be moved angularly transversely of the plane of the fork 7, as indicated by broken lines in Fig. 4, so as to clear said lug and be swung outwardly, as indicated by full lines in Fig. 1.

The clamping bar 9 is guided by the prongs 13 and co-operating guide lugs 18 for bodily movement toward or from the fixed clamping bar 8. The guide lugs 18 are formed in pairs on the ends of the movable clamping bar 9 and the prongs 35 13 extend longitudinally therebetween. Outwardly of the prongs 13, the guide lugs 18 of each pair are bent laterally toward each other and substantially completely embrace the respective 40 prongs 13.

One end of the screw rod 10 is rigidly secured to the movable clamping bar 9 at the longitudinal center thereof, and at its other end portion loosely extends through the hole 15. The thumb nut 11 is applied to the screw rod 10 between the movable clamping bar 9 and the crown piece 12 and engages said crown piece as a base of resistance to positively hold said bar against movement away from the fixed clamping bar 8. Obviously, when the thumb nut 11 is moved longitudinally 50 on the screw rod 10, away from the crown piece 12, the movable clamping bar 9 may be moved manually away from the fixed clamping bar 8, and at which time, the screw rod 10 will loosely 55 move endwise through the hole 15.

Formed in the ends of the movable clamping bar 9 are notch-like passageways 19 for the retaining lugs 16, and which passageways permit the clamping bar 9 to be removed from the 5 prongs 13. On each end of the clamping bar 9 is a pair of transversely spaced stop shoulders 20 for the respective prong 13. The passageways 19 are between the stop shoulders 20 of said pairs and are narrower than the transverse width of 10 the prongs 13. The purpose of the stop shoulders 20 is to hold the prongs 13 properly spaced and against inward lateral movement. In case the screw-threads on the rod 10 wear to such an extent that they are no longer efficient, said rod may 15 be removed from the mop head by removing the hinge pin 17 to detach the fixed clamping bar 8, and then withdrawing the movable clamping bar 9 from the prongs 13 and the screw rod 10 from the crown piece 12. With the removal of the 20 movable clamping bar 9 and its screw rod 10, a new bar and rod may be substituted therefor.

At the time the movable clamping bar 9 is removed from the prongs 13, the lugs 16 freely pass through the passageway 19.

What I claim is:

In a mop head, a fork having a pair of prongs provided at their ends with inturned retaining lugs, a relatively fixed clamping bar normally held on the retaining lugs, and a movable clamping bar between the prongs and having on each end a pair of guide lugs, said guide lugs, outwardly of the prongs, being bent around said prongs, said movable clamping bar having adjacent each end between the respective lugs a pair of transversely spaced stop shoulders and also having between each pair of stop shoulders a notch-like 15 passageway for the respective inturned lug, said prongs being wider, transverse to the plane of the fork, than the inturned lugs and the stop shoulders engaging the prongs.

ROY A. MYERS. 20
